UNITED STATES PATENT OFFICE

EDWARD C. HEGG, OF BUFFALO, NEW YORK, ASSIGNOR TO MOJONNIER BROS. CO., A CORPORATION OF ILLINOIS

DESIGN FOR A COMBINED MACHINE PEDESTAL, CASING, AND TABLE

Application filed September 16, 1929. Serial No. 32,767. Term of patent 14 years.

To all whom it may concern:

Be it known that I, EDWARD C. HEGG, a citizen of the United States, residing at Buffalo, county of Erie, and State of New York, have invented a new, original, and ornamental Design for a Combined Machine Pedestal, Casing, and Table, of which the following is a specification, reference being had to the accompanying drawings, forming a part thereof.

Fig. 1 is a side perspective view of a com-

bined machine pedestal casing and table showing my new design; Fig. 2 is a perspective view of the table end of the same; and Fig. 3 is a fragmentary perspective view of the same when viewed from the opposite end as shown in Fig. 2.

I claim:

The ornamental design for a combined machine pedestal, casing and table, as shown.

EDWARD C. HEGG.
